A. H. BELLAMY ET AL.
MANUAL KNITTING DEVICE.
FILED DEC. 19, 1921.

UNITED STATES PATENT OFFICE.

ARTHUR HARLEY BELLAMY AND CHARLES H. BELLAMY, OF PHILADELPHIA, PENNSYLVANIA.

MANUAL KNITTING DEVICE.

Application filed December 19, 1921. Serial No. 523,276.

To all whom it may concern:

Be it known that we, ARTHUR HARLEY BELLAMY and CHARLES H. BELLAMY, citizens of the United States, residing at Philadelphia, county of Philadelphia, and State of Pennsylvania, have invented certain new and useful Improvements in Manual Knitting Devices, of which the following is a specification.

- 10 One object of our invention is to provide a novel device which will afford amusement to children and enable them to quickly knit lengths of narrow material, commonly known among children as "horse line."
- 15 Another object is to make our improved device of a simple construction which can be readily grasped in a child's hand and which can be easily manipulated.

These objects, and other advantageous ends which will be described hereinafter, we attain in the following manner, reference being had to the accompanying drawing in which—

Figure 1 is a perspective view showing our improved device and the manner in which it is held in and manipulated by the hand,

Figure 2 is an elevation of our improved device,

Figure 3 is an enlarged section taken on the line 3—3 of Figure 2, and

Figure 4 is an enlarged top plan view of said device.

Referring to the drawing, our improved device includes a handle body portion 5 which is made cylindrical in form and has a central vertical passage 6, which, at its top, flares outward and intercepts the top edge surface 7 to provide a dished recess 8. The outer surface of the handle has grooves 9 cut therein; said grooves extending upward from the lower end to the top edge 7 and partly intercepting the recess 8. The handle portion 5 is preferably made of wood and we have illustrated four of the grooves 9. 45 Latch knitting needles 10 are slidably mounted lengthwise within the grooves 9 and have bent projections 11 which extend outward from the grooves laterally to positions beyond the peripheral surface of the 50 cylindrical handle portion 5. These latch needles may be of a type well known including latches 12 which are pivotally connected at 13 to the body portion 14 of the needles; the latches being movable upward to close 55 the space 15 between ends of the hooks 16

and the edge surface 17 of the body portions of the needles. The projections 11 are positioned between the lower ends 18 of the needles and the latch and hook portions.

A ring or band 19, preferably of seamless metal, firmly fits around the peripheral surface of the handle portion 5 at a position below the bottom thereof. This ring, as shown in Figures 2 and 3, forms a limiting stop downward for the projections 11 of the needles and when the projections 11 are in contact with the band 19, the hooks 16 of the needles are below the recess 8 and top edge 7. A second ring or band 20, preferably of seamless metal, snugly surrounds the handle portion 5 at a position to surround the hooks and latches of the needles when they are in their lowered positions with the latches closed against the hooks.

It will be noted that by arranging the grooves 9 and recess as above stated that the interception of the grooves with the recess will provide annularly arranged notches 21.

In the use of the device, the handle portion is grasped by the hand, such for example as the hand shown at 22 in Figure 1; the fingers surrounding the handle portion with the handle portion in engagement with the palm of the hand; the thumb of the hand being free for engagement with the projections 11 of the needles as will be hereinafter described.

In use, the object is to knit the yarn 23 into a length of knitted material and, as will hereinafter be more thoroughly described, as the material is knitted it can be pulled by the little finger 24 of the hand, which finger is positioned at a level below the lower end of the handle. To start the knitting operation the handle is held in the left hand so that the thumb can freely raise and lower the needles by engagement with the projections 11; the handle being slightly rotated after each knitting operation of a needle so as to move the next needle in series order in a position to be conveniently manipulated by the thumb. To commence work, the end of the yarn 23 is inserted downward through the passage 6 so that the end will project sufficiently below the lower end of the handle to allow it to be wrapped around the little finger 24. This is done to allow the work to be drawn down each time a stitch is made. The next operation is to push the needles upward as far

as they will go with the latches open. Then the yarn is wrapped once around each needle below the end of the open latch. The knitting can be commenced by placing the 5 yarn under the hook of a needle and closing the latch over it; then drawing the needle down with the thumb; then pushing the needle up again so that the stitch formed passes below the latch and with the hook 10 clear. This action is repeated successively upon the needles of the series in annular arrangement; it being noted that upon the lowering movement of a needle with the yarn inserted under the hook that the previously 15 formed stitch will close the latch to embrace the new portion of the yarn; the previously formed loop being arrested or stopped by the top surface 7 and the yarn bridging the notches 21 so that the closed hook 20 will be drawn through the previously formed loop or stitch and the latter will cast off and upon pulling the lower end by the finger 24, the previously formed loop in each instance will be moved toward the center of the passage 6 down the dished incline of the recess 8; the result being that the continuous knitting will produce a 25 knitted strip or line, such as shown at 25; this strip in the form illustrated being compact and substantially circular in cross section.

In the actual use of the device, it has been found that with little practice a child can quickly manipulate the same to produce an even knitted length of material and the device can be quickly and easily manufactured.

We preferably cover the handle portion with a sheet of material, such as paper 26, 35 so that the grooves below the band 19 will be covered and an even surface will be pro-

duced which is comfortable to the sense of touch and by making the handle out of wood, this strip can be pasted thereto so as to firmly adhere and furthermore the bands 45 19 and 20 can be forced thereon; the grooves allowing sufficient springing action to keep the band in place without further riveting or securing means.

While we have described our invention as 50 taking a particular form, it will be understood that the various parts of our invention may be changed without departing from the spirit thereof, and hence we do not limit ourselves to the precise construction set 55 forth, but consider that we are at liberty to make such changes and alterations as fairly come within the scope of the appended claim.

Having thus described our invention, what 60 we claim as new and desire to secure by Letters Patent is:—

A device of the character described including a handle having grooves formed in the peripheral surface of said handle; 65 needles slidably mounted in said grooves, said handle having a passage extending therethrough within the confines of said needles, said needles having projecting portions whereby they can be manipulated; and 70 bands surrounding said handle above and below the projections of said needles; substantially as described.

In testimony whereof we have signed our names to this specification in the presence 75 of two subscribing witnesses.

ARTHUR HARLEY BELLAMY.
